UNITED STATES PATENT OFFICE.

ARMOND J. MAYNARD, OF WATERBURY, CONNECTICUT.

SUBMARINE GRAPPLE.

1,374,512.

Specification of Letters Patent. Patented Apr. 12, 1921.

Application filed December 11, 1919. Serial No. 343,995.

To all whom it may concern:

Be it known that I, ARMOND J. MAYNARD, a citizen of the United States, residing at Waterbury, in the county of New Haven 5 and State of Connecticut, have invented certain new and useful Improvements in Submarine Grapples, of which the following is a specification.

This invention relates to improvements in 10 salvaging apparatus and it is the principal object of the invention to provide a novel form of submarine grapple capable of housing an operator or diver and being lowered into engagement with submerged objects, 15 whereby the same can be secured or connected thereto and then raised to the surface of the water; the device being of such construction as to enable the lowering thereof to great depths without danger thereto by reason of the water pressure encountered at 20 such depths.

Another and equally important object of 25 the invention is to provide a form of protective housing for an operator and from which the grappling means can be effectually actuated to engage the desired objects.

The invention consists, furthermore, in the novel arrangements and combinations of the parts of the device, as well as in the details of the construction of the same, all of 30 which will be more fully described in the following specification, and then finally embodied in the clauses of the claim, which are appended to this specification and which 35 form an essential part thereof.

In the drawings:

Figure 1 is a vertical section through the improved grappling device,

Fig. 2 is a bottom view thereof,

Fig. 3 is a top view of the same,

Fig. 4 is a fragmentary vertical section therethrough, and

Fig. 5 is a fragmentary detail in elevation showing the arrangement of the grappling means.

In the embodiment illustrated the grapple carrying diving bell includes a housing 1 which is a one-piece structure except for the closure 4 thereof. This housing consists of a tapered hollow body compartment 2 formed of suitable material to resist water pressure at great depths and is provided at its upper end with a laterally and outwardly extending integral flange 2^a which supports 55 an enlarged semi-spherical or dome shaped head 3. This flange 2^a also forms an instru-

ment board and is equipped with suitable transparent inserts 18 through which the diver may view his surroundings as will be hereinafter more fully described.

The dome shaped head 3 has a manhole formed in the top thereof to permit the diver to enter the bell and this manhole is closed by a suitable threaded closure 4 which is equipped with a handle 5 to facilitate its 65 insertion and removal. A plurality of apertured lugs 5, three being here shown, are formed integral with the upper portion of the head 3 and are engaged by chains 7 secured to a suitable coupling 8 with which the free end of a cable 9 is connected. This cable 9 is connected to a suitable lifting apparatus carried by a vessel and by means of which the diving bell or housing 1 may be raised or lowered.

Formed integral with the lower end of the tapered body portion 2 are a pair of laterally spaced depending plates 10 having grapple jaws 11 pivotally supported between them, said jaws being carried by longitudinally slotted shanks pivoted at 12 to said plates adjacent the junction of the jaws therewith. A pivot pin 14 carried by the lower end of an operating rod 15 extends through the slots 13 in the shanks of the 85 grapple jaws, said rod extending through an opening in the bottom of compartment 2 around which is arranged a packing 16 to form a fluidtight connection where the rod passes through the housing. If desired, 90 a handle 17 may be and preferably is arranged on the inner or upper end of the operating rod 15 for operating the grapple.

A plurality of inwardly tapered openings are formed in the lateral flange 2^a herein before described and serve to receive the transparent inserts 18 providing the usual "dead-lights." Arranged adjacent certain of these dead-lights 18 are the usual electrodes 19, which are engaged by electrical conductors 20, thereby affording the ordinary form of arc-light. It of course will be understood in this connection, that the conductors 20 are extended into engagement with a suitable source of electrical energy, not shown.

To facilitate the ascertaining of the water pressure encountered during the arranging or submerging of the device in a body of water, a pressure gage 21 is also arranged on the laterally disposed flange and of course 110 has suitable connection with the water. Further, to enable the operator in the hous-

ing to communicate with a person on the vessel to which the device is attached, I may and preferably do arrange therein the ordinary form of telephone 22, engaging electrical conductors 23 therewith, which in turn are extended into engagement with a similar device arranged on said vessel.

It will thus be seen that flange 2^a which operates to offset the lower edge of the 10 dome shaped head 3 from the upper end of the body 2 also performs the function of an instrument board carrying the articles above described.

In operation, the device is lowered into 15 a body of water to the desired depth and the operator, when the object desired has been reached, grasps the handle 17 and pulls the rod 15 upwardly, thus causing the jaws of the grapples 11 to engage said object. He 20 then signals the vessel by means of the telephone 22 in order that the diving bell and the object engaged by the grapple may be raised. Necessary light will of course be supplied by the arc-lamps 19, which as 25 hereinbefore stated, are arranged adjacent certain of the "deadlights" 18 and in this way, the operator or diver will be enabled to properly position the device with relation to the object to be salvaged.

30 Also the device can be constructed more rigid than a form fitting metallic suit, thereby permitting an operator therein to be

lowered to greater depths than is possible when such suits are used. In addition, the position of the grapple enables the operator 35 to pick up submerged objects without any undue maneuvering of the device for position.

Manifestly, the construction shown is capable of considerable modification and such 40 modification as is within the scope of my claim, I consider within the spirit of my invention.

I claim:

In an apparatus of the class described, a 45 one-piece housing having a body member tapered toward its lower end and being slightly larger than the body of a man, a dome-shaped head carried by the upper end of said body with an inwardly extending 50 flange connecting the lower edge of said flange with the upper end of said body offsetting one from the other and forming an instrument board, deadlights mounted in said flange, a manhole in the top of said dome, suspension means connected with said dome, and a grapple carried by the lower end of said body and equipped with an operating rod extending into the body to a 55 position convenient for actuation. 60

In testimony whereof, I affix my signature hereto.

ARMOND J. MAYNARD.
